UNITED STATES PATENT OFFICE.

HERMAN E. MANOFSKY, OF CHICAGO, ILLINOIS.

LINE HOLDER.

Application filed April 21, 1927. Serial No. 185,612.

This invention relates to new and useful improvements in line holders, and more particularly to a device of this character which is especially adapted for use in securing clothes lines, and the like, in order to retain them taut while in use.

One of the objects of my invention is the provision of a line holder whereby a clothes line or similar article may be readily engaged with the holder and drawn taut and then secured in this position, the device acting to securely retain the line in proper position regardless of weight placed thereon.

Another particular object of my invention is the provision of a line holder which includes in its construction, a supporting bracket having clamping jaws thereon, one of which is movably mounted upon the bracket and means is provided whereby to actuate the movable jaw to move the same toward and away from the stationary jaw, the stationary jaw being provided with engaging edges whereby to securely clamp a line or cable between the jaw faces.

A further object of my invention is the provision of a line holder which is extremely simple, durable and efficient in use for the purposes intended and whereby the parts may be quickly assembled or disassembled.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a plan view illustrating the use of my improved line holder;

Fig. 2 is a top plan view of one of the holders;

Fig. 3 is a front elevation;

Fig. 4 is a longitudinal section on the line 4—4 of Fig. 2; and

Fig. 5 is a vertical section on the line 5—5 of Fig. 4.

In the construction of my improved device, I provide an angular supporting bracket which includes a vertical portion 1 formed with perforations 2 for receiving fastening elements such as screws—or the like, to attach the vertical portion to a sup-

port. Extending longitudinally from the vertical portion intermediate its ends is the horizontal portion 3 which is braced by means of the substantially triangular wings 4. Provided on the upper surface of the horizontal part 3 is a stationary jaw member 5 having inclined side faces 6 and a transverse clamping face 7 providing substantially sharp engaging edges 8, the purpose of which will be hereinafter more fully set forth.

Slidably mounted upon the horizontal part 3 is an arm 9 provided at one end with a substantially arcuate jaw member 10 adapted to cooperate with the stationary jaw 5 for clamping a rope, cable, or the like, between the faces of the two jaw members. The horizontal part 3 is formed with a longitudinal slot 11 and the arm 9 is formed with a similar slot 12, one end of the slot 12 extending to the rear face of the movable jaw member 10, while the other end terminates adjacent the inner end of the arm. Extending upwardly from the horizontal part 3 upon opposite sides of the slot 11 are the perforated ears 13 which extend upwardly through recessed portions 14 in the side walls of the slot 12 and receive in the perforations, the pivot pin 15.

In order to actuate the jaw member 10, a cam lever 16 is provided having a cam-shaped end 17 pivotally mounted upon the pin 15 and adapted for movement through the slots 11 and 12. As the slot 12 in the arm 9 extends to the rear face of the jaw 10, the movement of the cam 17 in the slot 12 will cause the cam to bear against the rear face of the jaw 10 upon downward movement of the lever 16 so as to force the jaw 10 toward the jaw 5. As the lever 17 is raised to an inoperative position, it will be noted that the cam will engage the end of the slot opposite the jaw 10 and have a tendency to slide the arm 9 upon the horizontal portion 3 toward the vertical portion 1 for releasing the jaw 10 or moving the same away from the jaw 5.

The outer end of the lever 16 is provided with a transversely disposed finger piece 18 whereby pressure may be exerted upon the lever 16 when it is desired to tightly clamp a rope or cable between the clamping faces of the jaws 5 and 10. It will be apparent that by providing the inclined side faces 6 of the jaw 5 and the transverse clamping face 7 to form the engaging edges 8, a rope

or cable forced against these edges through movement of the jaw 10, will have a tendency to kink the rope or cable and thus securely hold the same against displacement 5 from between the jaws.

As clearly illustrated in Fig. 4, the outer edge of the cam 17 is formed with a substantially flat face 19 which is arranged adjacent the lever 16 and adapted to lie flat 10 against the outer surface of the jaw 10 when in operative position to provide a locking means for said cam.

It will be apparent that the device may be quickly and readily attached to a support 15 by extending fastening members through the perforations 2 and a rope or cable may be readily placed between the jaws 5 and 10 and securely clamped after being drawn taut.

As shown in Fig. 1, the clamp is used for 20 supporting several cross portions of a single line and should either one of the cross portions A or B become broken, the broken ends will be securely clamped between the jaws 5 and 10 so that the remaining portions will 25 still be retained taut. As illustrated, a number of holders may be arranged alternately with respect to each other, as shown in Fig. 1, and a single line used to provide several cross supporting members, and each cross 30 supporting member independently retained against movement by the clamping jaws. The device is of such construction that it is comparatively cheap to manufacture and the parts so arranged that they may be quickly 35 assembled or disassembled and the clamping parts so arranged as to be highly efficient in effectiveness.

Having thus described my invention, it is obvious that various immaterial modifications may be made in the same without departing from the spirit of my invention; 40 hence I do not wish to be understood as limiting myself to the exact form, construction, arrangement and combination of parts herein 45 shown and described, or uses mentioned.

What I claim as new and desire to secure by Letters Patent is:

1. In a device of the class described and 50 in combination, an angular bracket having its horizontal portion slotted, a stationary jaw on the horizontal portion, a movable jaw slidably mounted on the horizontal portion, a pivotally mounted cam for movement into the slot and engaging the second jaw to move 55 the same toward the stationary jaw, and means whereby to manually actuate said cam.

2. In a device of the class described and 60 in combination, an angular bracket, a stationary jaw on the horizontal portion of said bracket, inclined side faces on said jaw,

a transverse clamping face between the side faces providing sharp engaging edges, and an arcuate movable jaw adapted to cooperate with said engaging edges to clamp an object between said jaws. 65

3. In a device of the class described and in combination, a bracket having a slotted horizontal portion, a stationary jaw on the horizontal portion, a movable jaw, an arm formed integral with the movable jaw and 70 having a slot to align with the slot in the bracket, and a pivotally mounted cam for movement in said slots to engage the movable jaw and move the same in one direction, and engaging one end of the slot for moving 75 the last-mentioned jaw in the opposite direction.

4. In a device of the class described and in combination, a bracket having a slotted horizontal portion, a stationary jaw on the 80 horizontal portion, a movable jaw, an arm on the movable jaw having a slot to align with the slot in the bracket, spaced perforated ears on the bracket extending through the slot in the arm, the walls of the slot in the arm being recessed to receive said ears, and a cam pivoted between said ears for movement in said slots whereby to engage the movable jaw and move the same in one direction and engage one end of the slot in 85 the arm to move said last jaw in the opposite direction. 90

5. In a device of the class described, a pair of jaws therefor, one of said jaws having inclined side gripping faces and a transverse gripping face between said side gripping faces, the other jaw having an arcuate engaging portion adapted to cooperate with said first mentioned jaw, and means for 95 operating said jaws. 100

6. In a device of the class described and in combination, a jaw member, said jaw member having a slot, a second jaw member, said second jaw member having a slot, said slots being in alignment, a cam, said cam movable into said slots to engage one of said 105 jaw members to move said jaw members into closed position.

7. In a device of the class described and in combination, a jaw, said jaw having a bracket, said bracket having a slot, a second jaw, said second jaw having an arm, a slot in said arm, said last-mentioned slot in alignment with said first-mentioned slot, a cam, said cam movable into said slots to engage one of said jaw members for closing and opening said jaws. 110

In testimony whereof, I have hereunto signed my name.

HERMAN E. MANOFSKY.
